UNITED STATES PATENT OFFICE.

CHARLES A. KUENZEL, OF BUENA VISTA, COLORADO, ASSIGNOR TO THE KUENZEL GAS PRODUCER & SMELTER CONSTRUCTION CO., A CORPORATION OF WASHINGTON.

STEAMSHIP-FURNACE.

1,076,893.

Specification of Letters Patent.

Patented Oct. 28, 1913.

Application filed August 17, 1912. Serial No. 715,576.

To all whom it may concern:

Be it known that I, CHARLES A. KUENZEL, a citizen of the United States, residing at Buena Vista, in the county of Chaffee, State of Colorado, have invented a new and useful Steamship-Furnace, of which the following is a specification.

My invention consists of an improved gas-generator and furance for the boilers of a steamship employing oil as a fuel.

It further consists of improved means for protecting the generator.

It further consists of improved means for distributing the oil.

It further consists of other novel features of construction all as will be hereinafter fully set forth.

The invention is satisfactorily illustrated in the accompanying drawing, but the important instrumentalities thereof may be varied, and so it is to be understood that the invention is not limited to the specific arrangement and organization shown and described.

Figure 1 represents a somewhat diagrammatic side elevation of portions of the hull of a steamship equipped with my improved gas generating apparatus. Fig. 2 represents an enlarged sectional view of the generator.

Similar numerals of reference indicate corresponding parts in the figures.

Referring to the drawings, the reference numeral 1 indicates the hull of a steamship, in which one or more boilers, 2, of any desired or required type are mounted in any suitable or desired manner. The boiler here illustrated is of the return-flue type, having a furnace, 3, a bottom-flue 4, a return-chamber 5, flues, 6, and a smoke-chamber, 7, from which a stack, 8, extends. The bottom-flue has a lining, 9, of refractory material, such as firebrick, in its under side to retain the heat from the products of combustion passing through the flue and to protect the bottom of the boiler. An air-compressor, 10, driven by steam, internal combustion, or by any suitable power, is arranged to supply air under pressure to a tank, 11, and oil-tanks, 12, are arranged preferably in pairs, below the level of the furnace of the boiler. An air-pipe, 14, leads from the air-tank and is connected by branch-pipes 13 and 14^x, to necks, 15, upon the tops of the oil-tanks and having controlling valves 16, at such connections. The contents of the oil tanks may

thus be subjected to air-pressure. Pipes, 17, project through the necks of the tanks to near the bottoms of the same, and are connected to a common oil-supply pipe, 18, valves, 19, controlling such connections. A retort-structure, 20, is supported in the fire-door opening of the boiler-furnace, and is of the same construction as that disclosed in the Patent No. 1,039,549, issued to me on September 24th, 1912, upon application, Serial No. 646,258, for gas generator, filed by me on August 26th, 1911, and needs no specific description. Generally, such structure has four horizontal chambers, the upper one, 21, constitutes a vaporizing-chamber, the second one, 22, an air-heating chamber, the third one, 23, a superheating retort, and the fourth one, 24, a distributing retort, from which burners, 25, extend into the boiler-furnace. Air under pressure is conveyed from the air-distributing pipe, 14, through a pipe, 26, to an atomizer, 27, receiving oil from the oil-distributing pipe 18 through a pipe, 28, and said atomizer injects a jet of mixed oil and air into one end of the vaporizing chamber, from the other end of which the vapor passed through a pipe, 29, to a comminuting and mixing device, 30, fully described and illustrated in my said above patent application. Compressed air is conducted through a pipe, 31, to one end of the air-heating chamber, 22, in which it is heated and then conducted from the opposite end of the chamber, through a pipe, 32, to the comminuting and mixing device, and there mixed with the heated vapor and conducted through a pipe, 33, to the superheating retort, where the gas is superheated and passes to the distributing retort and out through the burners to be consumed in the furnace. The retort-structure is so supported in the fire-door opening, that a space, 34, is left open beneath the structure for admitting atmospheric air into the furnace. A checker-work, 35, of fire-bricks, having openings between them is secured by a plate, 36, and bolt, 37, to the face of the retort-structure to protect the same from the excessive heat of the flame in the furnace, while the bricks will transmit sufficient heat to heat the chambers and retorts and the gases therein.

When the burners are lighted after the generating apparatus has been started, the flame and products of combustion will be

carried around the boiler and through the boiler flues, and atmospheric air is admitted through the passage beneath the retort-structure to the flames in the furnace, aiding combustion and increasing the heat of the flames by the added amount of oxygen.

One oil-tank may be filled while oil is being forced out from the other tank, so that there need be no interruption in the operation of the apparatus while the oil-supply is renewed, nor need the tank be filled while there is pressure in the same. By having the oil-tanks beneath the level of the burners and retort apparatus, there can be no flooding of the furnace from gravity if by accident an oil-valve should be opened after the apparatus is stopped, as is liable where gravity feed is employed.

Having thus described my invention what I claim as new and desire to secure by Letters Patent, is:—

1. In an apparatus of the character stated,

a retort-structure adapted to fit in the fire-door opening of a furnace and comprising a vaporizing chamber, an air-heating chamber and superheating retorts, a burner extending into the furnace and connected to receive gas from said retorts, and a checker-work of firebrick and supported against the inner face of said retort-structure.

2. In an apparatus of the character stated, a furnace having a fire-door opening, a retort-structure secured to fit in and partly close the upper part of said opening and thereby form an air-inlet beneath it and constructed with air and gas heating chambers, burners extending into the furnace from said retort-structure, and a firebrick checker-work supported against the inner face of said retort-structure.

CHARLES A. KUENZEL.
